UNITED STATES PATENT OFFICE.

ALBERT P. McGRAW, OF McGRAW, NEW YORK.

GARMENT-STIFFENER.

SPECIFICATION forming part of Letters Patent No. 637,995, dated November 28, 1899.

Application filed July 5, 1899. Serial No. 722,888. (No model.)

To all whom it may concern:

Be it known that I, ALBERT P. McGRAW, a resident of the village of McGraw, State of New York, have invented a new and useful 5 Improvement in Garment-Stiffeners, which invention is fully set forth in the following specification.

My invention relates to stiffeners for garments, and is more particularly designed for 10 use in connection with corsets, waists, or skirts.

The particular object of the invention is to provide a stiffener of the character described, which shall efficiently perform the functions 15 of a stiffener in the class of garments mentioned, but which shall nevertheless be economical to manufacture.

With this object in view the invention consists of a stiffener composed of one or more 20 thicknesses of fabric or paper folded, with as many turns or folds as may be found desirable, around a long strip of stiffening material and treated with a suitable size or stiffening cement and is flattened and the folds 25 thereof suitably secured to the stiffening material and to each other by a line of stitching or by cement. Preferably the fabric or paper strip is folded around a suitable filling of horsehair, sisal, or other similar filling, which 30 filling may be, if desired, in the form of woven or other fabric.

I have illustrated the invention in the accompanying drawings, in which—

Figure 1 is a perspective view of one of my 35 stiffeners, showing the parts stitched together, except at one end, where it is opened out to show the filling material. Fig. 2 is a perspective view of one of the stiffeners, the folds being secured together by cement instead of stitching. Fig. 3 is a perspective view of one form of stiffening-strip. Fig. 4 is an enlarged end view of Fig. 1.

Like letters refer to like parts in all the views.

Referring to the drawings, A is a strip of suitable material of such width that when folded, as shown, and flattened out by passing through rolls or otherwise it will be of the width of the desired stiffener.

B B are strips of filling material, as horse-hair or sisal. These strips may be, and preferably are, in the form of narrow strips of fabric cut slightly narrower than the desired width of the finished stiffener. As shown in Fig. 1, two of such strips B are used; but any 55 number of such strips as may be found desirable may be used, preferably in connection with a suitable sizing or cement to supply additional stiffness.

C is a line of stitching passing through the 60 folds of the envelop or folded strip A and also through the filling-strips B B when the same are used. Instead of this line of stitches I sometimes employ a suitable cement, as rubber cement, for example, to secure the folds 65 smoothly in place.

In manufacturing my improved stiffeners I cut continuous strips of the material A, which I pass through a folding-machine, where it is folded around the stiffening-strips B, after 70 which pressure is applied by rolls or otherwise to produce the shape of an ordinary bone or corset-steel, after which it is stitched, if stitching is employed. If cement is used, as in the case shown in Fig. 2, such cement is 75 preferably continuously applied as the strip A is in the act of being folded. The strip having been folded, flattened, and stitched or cemented is cut into any desired lengths ready for use.

It will be seen that by my invention a stiffener of any desired degree of stiffness and elasticity may be secured at a minimum cost.

Having thus described my invention, what I claim, and desire to secure by Letters Patent, is—

A garment-stiffener consisting of folds of material inclosing a stiffening-strip, the overlapping edges of the folds and the stiffening-strip being all secured together by a single 90 line of stitching.

In testimony whereof I have signed this specification in the presence of two subscribing witnesses.

ALBERT P. McGRAW.
